TELEPHONE STAND

David E. White, Cleveland, Ohio

Application May 22, 1941, Serial No. 394,730

4 Claims. (Cl. 179—159)

This invention is directed to an improved telephone stand having a cradle for the reception of the telephone receiver, commonly referred to as the French type of telephone stand.

An object of the invention is the provision of a separate manually operated means for connecting and disconnecting the current to the receiver or head set in order that the telephone may be connected and disconnected when the receiver is removed from or partially removed from the cradle of the receiver stand.

Another object of the invention is the provision of a separate manual operator for telephone sets of the above type that may be permanently attached to the set, or in another form may be attached to a telephone set.

Still another object of the invention is the provision of a manual switch operator which is in a convenient position for operation by a finger of the telephone user, and without interference with the receiver as it is removed from or placed on the cradle of the stand.

Other objects will appear hereinafter in the specification.

In the drawings:

Figure 1 is a perspective view of one form of the present invention.

Figure 2 is a detail view of the form shown in Figure 1 with part of the stand shown as broken away to show the relative position of the parts.

Figure 3 is a view similar to Figure 2, but showing a modified form of the invention.

Figure 4 is a plan view of another modification of the invention.

Figure 5 is a side elevation of the form shown by Figure 4, with some of the parts in section.

Figure 6 is a further modification of the invention in front elevation partly broken away, a part of the stand being shown in section, and

Figure 7 is a top or plan view of the modification shown in Figure 6, one of the parts thereof being shown in section.

In business establishments, as is the usual practice, an operative or a stenographer answers the telephone and connects or notifies the person called. After the person called has lifted the receiver of his telephone, the stenographer usually replaces her receiver in the cradle of her telephone stand. Such replacement of the telephone receiver results usually in an objectionable noise, which is heard by both the caller and the person called. This is due to the fact that the telephone receiver is dropped onto the cradle by the stenographer as she "hangs up." The present invention does away with the annoyance

and the interference caused by the stenographer dropping the receiver back onto its place in the cradle. When using a device of the present invention the operator merely depresses the manual operating member, and holds it depressed while replacing the telephone receiver in the cradle.

In Figure 1, which shows one form of the invention, the hand set or stand 1 is provided with the usual cradle members 2 and a plunger type switch member such as the depressible rods 3, either one of which when depressed serves to disconnect the set from the line.

Pivoted on one side of the stand 10 is a switch operating member 4, constructed preferably of sheet metal. The numeral 5 indicates the pivotal mounting for the operating member. There is a washer or stud member 6 for spacing the operating member 4 from the telephone stand 1. This stud member may be integral with the stand, but preferably it is a separate part. Forming part of the operator is a vertical extension 7 and an upper horizontal extension or ear 8. A lower horizontal extension or ear 9 is located on a line with the bottom of the operating member. Preferably, as shown, the ear 9 is remotely located with reference to the operator pivot 5.

In the construction illustrated, the switch operating member may readily be attached to telephone sets now in use by boring a small screw threaded hole in the side of the telephone set stand for the reception of the pivot 5, which after the operating member 4 and washer 6 are placed thereon, is screwed in the said hole and the parts assume the position shown in Figure 1, with the ear 8 resting upon the top of the left hand rod 3. It is to be understood that the operating member 4 turns on a cylindrical portion of the pivot 5, that is, the portion not provided with screw threads. Most machine screws are provided with a cylindrical portion near the head thereof.

It will be noted that no modification of the telephone stand is required other than the boring of a hole suitable for the reception of the screw pivot 5, and that the operating member itself may be made at a cost of only a few cents, and its attachment to either side of the stand may be quickly and easily accomplished. When in the position shown the receiver may be replaced on the cradle while the operating member is held depressed by the finger of the user. To disconnect the telephone connection, it is only necessary to push downwardly with one finger on the

ear 9. This forces the rod 9 down as the ear 8 is forced down, thereby disconnecting the telephone. Thus no sound is heard at either end of the telephone line except the slight click made when the instant telephone receiver is disconnected, and the disagreeable sound, which often momentarily interrupts conversation on the telephone line, due to the replacing of the receiver on the stand cradle, is entirely done away with.

In the form shown in Figure 3 the stand 10 is provided, as in Figure 1, with cradle members 11, only one of which is shown, and the plunger type switch having depressible rods 12, only one being shown for purposes of illustration. The upper end of this rod may be modified by reducing the upper end thereof to provide a screw threaded stud portion, although it is to be understood that the threads may be omitted and any other suitable means substituted for attaching the operating member to the switch operating rod. The operating member 14 has an upper horizontal ear 15 having a recess or hole 16 which, as stated above, may be attached to the rod in any suitable manner, such as by a threaded connection shown. The operating member may be depressed to force down the plunger type switch having the rod 12 to thereby disconnect the telephone, by pressing downwardly with the finger on the lower horizontal ear 17, without interfering with the operation of removing or replacing the receiver from or to its position of rest on the cradle of the stand. The results are the same as those described in connection with Figures 1 and 2.

The telephone stand shown in Figures 4 and 5 is not as modern in its construction as that shown in Figure 1. This stand 18, still widely used, is provided with cradle members 19, a single vertically movable switch operating rod 20, centrally located with reference to the cradle members 19, and extensions 21 integral with the rod 20.

The invention shown in Figures 4 and 5 consists in providing an operating member 22 having an upper horizontal ear or extension 23, and a lower horizontal ear or extension 24, which latter may be depressed by the finger of one hand, while as is usually the case, the other hand holds the telephone receiver (not shown). The upper ear is an integral part of the extensions 21 as shown, although I do not desire to be limited to a construction where the operating member is integral with either the rod 20 or the extensions 21, as it may be attached in any suitable manner to either of these parts, as will be appreciated by reference to Figure 3.

In Figures 6 and 7, which are partial views of a telephone set of the type shown in Figure 1 that has rods at both sides of the receiver cradle, there is shown a section of a stand 25. Only a part of one of the cradles 26 and one switch operating rod

27 is shown. This rod is preferably provided with a head 28, which is the means by which it may be depressed and rotated by the hand of the user. The top 29 of the stand is provided with an aperture 30 through which the rod 27 moves, and the aperture is shown as having a notch or groove 31 through which the stud 32 moves, the stud being permanently attached to the rod 27. The rod 27 may be depressed and then rotated to engage the underside portion of the top 29 as shown in dotted lines in Figure 7. In this position the rod 27 will remain depressed until it has been rotated again to the position where the stud 32 will move upwardly within the notch 31, whereupon the rod with its stud will move upwardly (under the force of one or more springs provided in the standard telephone set) to connect the telephone into the circuit.

It will be noted that the invention shown in Figures 6 and 7 is somewhat different from that illustrated in the other figures. The head set must be entirely removed, in the construction of Figures 6 and 7, before the rod 27 can be manually operated. After the head set has been removed, the switch may be opened and held in this position by the stud 32, and an additional manual operation is required before the switch may be opened, in addition to any operation of removal of the head set from the cradle.

One of the advantages of the construction illustrated in Figures 6 and 7 is that the knocking over of the stand by accident will not open the telephone circuit.

I desire to be limited only to the extent set forth by the appended claims.

I claim:

1. In a telephone hand set having a cradle and a plunger type switch member in said set and a hand telephone adapted to actuate said switch member when placed on said cradle, the combination with said set of an operating member, a manually operable part on said operating member adapted to be operated prior to placing the hand telephone on the cradle to actuate said switch member in a downward direction to thereby disconnect the telephone connection, said manually operable means being displaced laterally with respect to the axis of said cradle.

2. The structure of claim 1, wherein said operating member is provided with means pivotally mounting the same on said hand set.

3. The structure of claim 1, wherein the operating member is provided with means whereby said operating member is arranged to reciprocate with said switch member.

4. The structure of claim 1, wherein said operating member and manually operable means include a plurality of steps, one of said steps forming said manually operable means.

DAVID E. WHITE.
